UNITED STATES PATENT OFFICE.

CHESTER HILL, OF GENEVA, OHIO.

ELECTRIC SWITCH.

1,117,046.

Specification of Letters Patent. Patented Nov. 10, 1914.

Application filed May 15, 1912. Serial No. 697,454.

To all whom it may concern:

Be it known that I, CHESTER HILL, a citizen of the United States, residing at Geneva, in the county of Ashtabula and State of Ohio, have invented certain new and useful Improvements in Electric Switches, of which the following is a specification, reference being had therein to the accompanying drawing.

10 This invention relates to signals and has special reference to an electric switch to be used in connection with a signal system.

Another object of this invention is the production of a switch which is simple in 15 construction, efficient in operation and consists of the minimum number of parts.

With the above and other objects in view, this invention consists in general of certain novel constructions, combinations and arrangements of parts, as will be hereinafter 20 fully described, illustrated in the accompanying drawings, and specifically claimed.

In the accompanying drawings, like characters of reference indicate like parts 25 in the several views, and Figure 1 is a side elevation of one of the circuit closing devices. Fig. 2 is an end elevation thereof. Fig. 3 is a plan view thereof. Fig. 4 is a detail view of a portion of the circuit 30 closer. Fig. 5 is a detail section on the line 9—9 of Fig. 4. Fig. 6 is a detail section on the line 10—10 of Fig. 5. Fig. 7 is a view showing a modified form adapted for use in connection with a steam railway.

35 In the form of operating device herein illustrated there is provided a set of vertical supports 30 insulated from the trolley wire 21 and from a second wire 31 which may be a feed wire or the like. These supports are 40 connected at their upper ends by means of the plate 32 whereon is mounted the casing 33 of a three-pole switch.

In the switch herein disclosed there is 45 provided a shaft 34 whereon is mounted a ratchet 35. Within the casing is an insulating plate 36 wherethrough this stem passes and on this plate is a contact ring 37 which forms one pole of the switch. Within the casing is also a second contact ring 38 50 which forms the second pole of the switch. A third pole 39 is likewise provided within the casing, and carried on the shaft 34 but insulated therefrom is a boss 40 wherefrom extends an arm 41 carrying a contact point 55 42. This arm 41 rotates against the contact

ring 38 so that by the rotation of the ratchet 35 the arm may be brought to such position that the points 42 will contact with the pole 39. On the shaft 34 is likewise a second boss 43 carrying a similar contact provided 60 arm 44 which rotates against the ring 37. These arms extend in opposite directions from the axis of the ratchet so that their contact points are alternately brought into engagement with the pole 39. 65

In order to actuate the ratchet upon the passing of a trolley there is shown in Fig. 1 a hinge 45 secured to but insulated from the plate 32. Hinged to this hinge 45 is a plate 46 of sheet metal which is curved longitudinally and has its central portion resting on the trolley wire 21. The free end of this plate is upwardly curved and extends beneath the casing 33 and resting on this free end is the lower portion of an operating 75 plunger 47 carrying an insulating extension 48. This plunger extends upward into the casing and has an upper end 49 to which is pivoted a rack arm 50 held by spring 51 in engagement with the ratchet 35. Now, upon 80 the passage of a car the trolley contacts with the underside of the plate 46 and raises this plate to such an extent that the ratchet is caused to revolve through an arc of 180°, thereby changing the arm in contact with 85 the pole 39. By this means, as each car passes through the protected portion of the track the poles of the switches are reversed, first one switch and then the other being actuated. 90

In the modified form, shown in Fig. 7, the plate 46 is inverted and a suitable contact roller 52 is supported beneath the car and arranged to strike the plate. In order to hold the plate raised a spring 53 is provided beneath the same and in order to hold the plunger 47 raised a guide 54 is provided for the plunger and between the head of the plunger and this guide is a spring 55. 95

There has thus been provided a simple 100 and efficient device of the kind described and for the purpose specified.

It is obvious that many minor changes may be made in the form and construction thereof without departing from the material 105 principles thereof and it is therefore not wished to confine the invention to the exact form herein shown and described but it is wished to include all such as come within the scope of the appended claims. 110

Having thus described, the invention, what is claimed as new, is:—

1. A switch of the class described comprising a plurality of vertically extending supporting standards, a plate fixedly secured to the upper ends of said standards, means for supporting said standards, whereby said plate will be held at a spaced distance above said means, a bowed operating plate hingedly secured to the lower side of said first-mentioned plate, said operating plate adapted to normally rest upon said means, and means attached to said operating plate adjacent the free end thereof for closing a circuit, said operating plate adapted to be engaged and swung upon said first-mentioned plate whereby said circuit closing means will be operated.
2. In a switch of the class described, the combination with an insulated supporting plate, a bowed operating plate hingedly secured to said supporting plate, a supporting casing carried upon the upper portion of

said supporting plate, a shaft revolvably mounted upon said casing, a plurality of 25 contact points carried by said casing, means for supplying electric current to said points, a plurality of arms fixedly secured upon said shaft, said arms provided with contact points, a ratchet wheel fixedly secured upon 30 the outer end of said shaft, an operating plunger secured to said operating plate adjacent the free end thereof, said plunger provided with a rack portion adapted to engage said ratchet wheel, means for supplying electric current to said shaft, whereby when said operating plate is swung said plunger will rotate said ratchet wheel whereby said points will engage each other for closing the circuit.

In testimony whereof I hereunto affix my signature in presence of two witnesses.

CHESTER HILL.
